UNITED STATES PATENT OFFICE.

ROBESON B. WOLCOTT, OF LAKewood, OHIO, ASSIGNOR OF ONE-HALF TO FRANK L. SESSIONS, OF LAKewood, OHIO.

ELECTRIC FLASH LIGHT.

Application filed December 18, 1924. Serial No. 756,689.

In the past one of the most troublesome and costly parts of a standard flash-light has been the switch mechanism. My invention makes possible an extremely simple switch 5 which can be made and assembled at very low cost. It is adapted to be used on flash-lights having metal battery cases as well as on those having battery cases made of fibre or other insulating material.

10 It will be understood that although this specification describes my invention in connection with a standard pocket type flash-light it may be used for any purpose for which it is suitable.

15 Among the objects of my invention are: The provision of a flash-light, adapted to use standard bulb and battery, having a switch mechanism which can be manufactured at low cost; the provision in a flash-light having a metal case, of a switch mechanism no part of which is riveted or otherwise rigidly attached to the metal case, thus reducing the assembly cost to a minimum; the provision of a switch mechanism for 20 25 flash-lights which is adapted to make and break the contact between the battery and the base or center contact of the bulb.

These and other objects are attained by the use of my invention herein described and 30 shown in the accompanying drawings, in which:

Fig. 1 is a longitudinal section through a flash-light having a metal case embodying my invention with the switch in the "on" 35 position;

Fig. 2 is a fragmentary plan view of the flash-light shown in Fig. 1 with the switch removed;

Fig. 3 is the same view as Fig. 2 except 40 with the switch in place and in the "on" position;

Fig. 4 is a sectional view on line IV—IV of Fig. 3;

Fig. 5 is a longitudinal section of a flash-light having a fibre case. In this view the switch is in the "off" position;

Fig. 6 is a fragmentary plan view of the flash-light shown in Fig. 5;

Fig. 7 is a section on line VII—VII of Fig. 6;

Fig. 8 is a fragmentary end view of the flash-light shown in Fig. 5 with end cap and battery removed.

Referring to the drawings, the cylindrical 55 metal case, 1, has threads formed on each

end to receive the threaded end caps, 2, and 3. The end cap, 2, is formed so as to hold the lens, 4, in position and the lens, 4, in turn holds the reflector, 5, in place. The reflector, 5, is formed with a flange at its large 60 end so that when end cap, 2, is screwed on to the metal case, 1, the lens, 4, is forced against the flange of the reflector, 5, and the flange is held against the end of the cylindrical metal case, 1, thus making an unyielding electrical 65 contact between the case and the reflector.

The reflector, 5, has threads formed at its smaller end to hold the electric light bulb, 6. The end cap, 3, screws on to the opposite end of the case, 1, from the lens. It has a solid 70 base against which one end of the helical spring, 7, rests. The other end of the spring, 7, pushes against the base of the battery, 8, tending to push the battery, 8, to the other end of the metal case, 1, and also 75 making permanent the electrical connection between the cap, 3, and the base of battery, 8, throughout the range of movement of the battery, 8, in the case, 1.

It will be seen that the spring, 7, makes 80 yielding pressure between the center terminal of the lamp, 6^a, and the center terminal of the battery, 14.

A slot, 9, is cut in the metal case, 1, near the front or lens end. The button, 10, has 85 a stem, 11, which extends through slot, 9, into the inside of the metal case, 1. Stem, 11, passes through the roller, 12, and the end is riveted to hold roller, 12, in place. Roller, 12, is preferably made of insulating material, but it may be made of metal and it may be insulated from the stem, 11, by suitable insulation. The plate, 13, may be formed to conform with the curve of the metal case, 1, and serves to cover the slot, 9. 90

When the button, 10, is in the position shown in Fig. 3, that is, when it is in the forward or "on" position, the spring, 7, pushes the battery, 8, against the center terminal of the lamp, 6. The circuit is then 100 completed from the base of the battery through the spring, 7, the cap, 3, the metal case, 1, the reflector, 5, the outer terminal of the lamp, 6, through the lamp filament to the center terminal, 6^a, of the lamp, 6, 105 and the battery terminal, 14.

The slot, 9, in the metal case, 1, is so shaped that when the button, 10, is moved back from the position shown in Fig. 3 the slot, 9, guides the stem, 11, causing the roller, 110

12, to push the battery, 8, back against the force of the spring, 7, and out of contact with the center terminal, 6^a, of lamp, 6. This opens the circuit and the lamp goes out.

When the button, 10, is in its extreme back or "off" position, it is held there by the shape of the slot, 9, which is made slightly re-entrant to engage, stem, 11, and the battery, 8, is locked out of contact with lamp, 6.

When the switch is in the back or "off" position a side push on the button, 10, will release the stem, 11, from the notch or re-entrant portion in slot, 9, and spring, 7, will push the battery, 8, forward into contact with the center terminal of lamp, 6.

Fig. 5 shows a flash-light similar to the one shown in Fig. 1 except that it has a fibre or cardboard case, 15, instead of the metal case, 1. The threads on the ends of the case, 15, are formed in the material of the case and the end caps, 2, and 3, lens, 4, reflector, 5, lamp, 6, spring, 7, and battery, 8, are assembled in the same manner as described in connection with the metal case type shown in Figs. 1, 2, 3 and 4.

A hole, 16, may be cut in the case, 15, to accommodate the movements of the stem, 11. A strip of thin metal, 17, formed to fit the inside of case, 15, extends lengthwise of case, 15, and is flanged over on the ends to form end surfaces adapted to contact with the flange of the reflector, 5, and the spring, 7, or cap, 3. In the drawings this strip of thin metal, 17, is shown covering about one third of the inner surface of the case, 15, but it is evident that it can be made of any desired width. The strip, 17, is held in place by the rivets, 18 and 19. These rivets, 18 and 19, also serve to hold the metal plate, 20, in place on the outside of the case, 15. This plate, 20, is shaped to fit the outside of the case, 15, and has a slot, 9^a, shown in dotted lines in Fig. 6, cut in it to guide the stem, 11, of button, 10. Plate, 13, has a hole in its center adapted to receive stem, 11, and serves to cover the slot, 9^a, in plate, 20, as in the construction in which the metal case, 1, is used.

The hole, 16, in case, 15, is covered by plate, 20. A hole, 16^a, corresponding to hole, 16, is cut through the metal strip, 17. The metal strip, 17, acts as a conductor connecting the spring, 7, or cap, 3, and the reflector, 5.

In Fig. 5 the switch mechanism and the battery are shown in the "off" position. The spring, 7, is compressed and the battery, 8, is held back out of contact with the lamp, 6, by the roller, 12.

It will be seen that my flash-light is composed of very few and inexpensive parts and that it is of simple construction, easy to operate. When the button, 10, is held in

the off position by the hook shape of the rear end of slot, 9, a push of the button to the side releases it and the spring, 7, then pushes the battery, 8, into contact with the center terminal of the lamp, 6. If it is desired to give a series of flashes with the lamp, it is only necessary to pull back on the button enough to break the contact between the lamp and battery, then release the button and allow the spring to re-make the contact. The lamp will always stay lighted unless the button is pulled back.

My flash-light switch is reliable. It has no electrical contacts. The circuit is broken at a point where there must be a separable contact, between the battery and the lamp. The electrical circuit, therefore, has at least one less joint than obtains in flash-lights where the usual form of electric contact switch is used.

I claim:

1. In an electric flash-light, a tubular metallic case open at both ends, an electric light mounted in one end of said case with its side contact electrically connected with said case, an end cap adapted to be attached to the opposite end of said case, a battery adapted to fit in said case between said end cap and said electric light, a spring in said end cap adapted to push against the base of said battery to normally hold the top end of said battery in contact with the base of said electric light and means comprising a movable element extending through the case and pressing against the top end of the battery to move said battery against the pressure of said spring and break the contact between said end of said battery and said base of said electric light.

2. A flash-light comprising a battery case, 105 an incandescent bulb supported in one end of said battery case, a battery in said case movable longitudinally, unyielding electrical connections between one terminal of said bulb and one terminal of said battery, yielding means for normally holding the other terminal of said battery in contact with the other terminal of said bulb and means comprising a movable element extending through the case and pressing against the bulb-engaging end of said battery to move said battery against said yielding means to break the contact between the battery and the bulb.

3. In a flash-light, a case, an incandescent lamp supported in one end of said case, a 120 battery adapted to fit in said case and be movable longitudinally thereof, one terminal of said battery being in permanent electrical connection with one terminal of said lamp, spring means to normally hold the other terminal of said battery in contact with the other terminal of said lamp, a cam slot in said case, a pin extending through and movable in said slot having an operating button on its outer end, and having its inner end 125

- adapted to engage the end of said battery, said pin being adapted when in one position to permit said battery terminal to contact with said lamp terminal and when in another position moving said battery to break said contact between said lamp and said battery, said slot having a re-entrant portion adapted to hold said pin in said second-named position.
4. A flash-light comprising a battery, a battery housing, an electric light bulb supported by said battery housing, permanent electrical connection between one terminal of said electric light bulb and one terminal of said battery, a pin extending through a slot in said battery housing, said slot in said battery housing being shaped to guide the movement of said pin, said pin being adapted when in one position in said slot to hold said battery in such a position in said battery housing that the circuit between said lamp and said battery is broken and when in another position to allow said battery to be in such a position in said battery housing that said circuit between said lamp and said battery is completed and spring means in said battery housing tending to hold said battery in said last named position.
5. A flash-light comprising a battery, a battery housing, an electric light bulb, permanent electrical connection between one terminal of said electric light bulb and one terminal of said battery; spring means normally holding the other terminal of said battery in contact with the other terminal of said electric light bulb, battery moving means engaging the lamp-contacting end of said battery and passing through said casing above the lamp-contacting end of the battery and operable from the outside of said battery casing, for moving said second named battery terminal out of contact with said second named electric light bulb terminal and means for locking said battery moving means in position to hold said battery terminal out of contact with said electric light bulb terminal.
6. In an electric flash-light case, a slot extending lengthwise of said case, a pin adapted to slide in said slot and be guided by said slot, an operating button on the outer end of said pin, a roller button on the inner end of said pin, and means for locking said pin to prevent movement thereof in a direction longitudinal of said case.
7. In combination with a tubular case battery flash-light, a flash-light switch comprising a pin slidably held in a slot in said tubular case, said slot being so shaped as to allow said pin to move lengthwise of said case, said pin having an operating button on its outer end and having its inner end adapted to make contact with one end of a battery in said tubular battery case, spring means adapted to push against the opposite end of said battery to keep said first named end of said battery in contact with said inner end of said pin, and means consisting of a re-entrant portion of said slot adapted to hold said pin from longitudinal movement.

ROBESON B. WOLCOTT.
